United States Patent Office

Des. 213,541
Patented Mar. 18, 1969

213,541

BOTTLE OR SIMILAR ARTICLE

Murray L. Cowan, Norwood, Mass., and James Malcolm Gear, Providence, R.I., assignors to Textron Inc., Providence, R.I., a corporation of Delaware

Filed Oct. 23, 1967, Ser. No. 9,103

Term of patent 14 years

U.S. Cl. D9—76
Int. Cl. D9—01

FIG. 1

FIG. 2

FIG. 1 is a perspective view of a bottle or similar article, showing our new design;

FIG. 2 is a front elevational view;

FIG. 3 is a rear elevational view;

FIG. 4 is an elevational view looking from the right of FIG. 2; and

FIG. 5 is a top plan view thereof.

We claim:

The ornamental design for a bottle or similar article, substantially as shown.
